UNITED STATES PATENT OFFICE.

JOSEPH O. RICHARD, OF DETROIT, MICHIGAN, ASSIGNOR TO HAYES MANUFACTURING COMPANY, OF DETROIT, MICHIGAN, A CORPORATION OF MICHIGAN.

JIG FOR MARKING AND DRILLING FENDERS.

Application filed March 25, 1922. Serial No. 546,914.

To all whom it may concern:

Be it known that JOSEPH O. RICHARD, citizen of the United States, residing at Detroit, in the county of Wayne and State of Michigan, has invented certain new and useful Improvements in Jigs for Marking and Drilling Fenders, of which the following is a specification.

This invention relates to a fender jig for marking and drilling fenders in the process of construction. Automobile fenders are universally made by a stamping operation, usually a drawing operation. In order to draw the crown in a fender it is necessary to pinch the fender at the edges with what is usually called a draw ring. This requires the use of surplus metal that has to be trimmed off. This trimming is done with an ordinary cutter and the work has to be guided through the cutter by the workman. Hence it is necessary to properly mark the fender so that the workman will be able to cut this accurately. Furthermore, the fender is drilled so the holes act as guides for trimming the ends and punching the slots thru which it is attached to the wheel housing.

It is the object of the present invention to provide a jig which will serve as a marking jig and also a drilling jig. This jig is also so formed that part of it may be replaced to change the jig for similar fenders without having to build an entirely new jig.

In the drawings:—

Fig. 1 is a side elevation of the jig.

Fig. 2 is an elevation in detail of one end showing the lock.

Fig. 3 is a plan view of the male member.

Fig. 4 is a cross section thru the fixture and the rough fender.

Fig. 5 is a plan view of a crown fender after it has been drilled and marked.

Fig. 6 is a plan view of the female die. *a* designates a casting which is the male member of the jig and which is provided with transverse ribs *b* which are the supporting surfaces for the under side of the fender. The female member of the jig is guided in vertical reciprocation on the rods *c* and can be raised or lowered by compressed air through the instrumentality of the air cylinder and piston. The upper female member is provided with the apron *x* and may be caused to descend upon the fen-

der to indicate to the workman where it should be marked to be trimmed. The rear fenders usually have to be cut into quite deeply along the inside edge to make them conform to the body where they are attached to the wheel housing. This line is marked *e* upon the fender shown in Fig. 5.

One manufacturer of automobiles often has several models of cars provided with fenders that differ only in small details. It is rather wasteful to have to make a new set of dies or a new jig simply on this account. I take care of this situation by providing a sectional jig female member. The rear section *f* may be taken out and another section substituted for it which embodies any difference in details that appertains to different fenders for the same line of cars.

This rear section of the female member also forms a drill jig. It is provided with suitable openings *g* through which the drilling tool may be inserted to provide the pilot holes *h* for aiding in punching the slots through which bolts are passed to secure the fender to the wheel housing; similarly, the female jig member may be provided with openings to drill the holes *i* in the end of the fender for providing pilot holes to receive pilot pins in dies for cutting off the ends of the fenders.

A sort of toggle clamp *j* may be used in the ends of the male member for clamping the female member in place while the marking and drilling operation is performed.

What I claim is:

1. A jig for the purpose specified, comprising a male member adapted to support a stamping, and a female member, means for guiding the same in vertical reciprocation with respect to the male member, the female member arranged to descend on said male member, and said female member having a periphery which acts as a marking pattern by which the line to trim the stamping is placed upon the fender.

2. A jig for the purpose specified, having in combination, a male member arranged to support a stamping, and a female member or pattern, means for guiding the same in vertical reciprocation with respect to said male member so that the female member or pattern may descend upon the stamping and the male member, the said female member having a periphery which acts as a

marking pattern by which the line to trim the stamping along is marked upon the stamping.

3. A jig for the purpose specified, having in combination, a male member adapted to support a stamping, and a female member or pattern arranged to descend upon the stamping supported by the male member, the said female member having detachable sections so that a section may be replaced to make the jig applicable to stampings differing somewhat in design or dimensions.

4. A jig for the purpose specified, having in combination, a male member arranged to support a stamping, a female member, means for guiding the same in vertical reciprocation with respect to the male member, and means for raising and lowering the female member, said female member arranged to descend upon the stamping supported upon the male member and having a periphery which acts as a marking pattern whereby the trimming line may be marked upon the stamping.

25 5. A jig for the purpose specified, having in combination a male member arranged to support a stamping and a female member, means for guiding the same in vertical reciprocation with respect to the male member, the female member arranged to descend upon the stamping and having a periphery which acts as a marking pattern and provided with apertures; and the said female

member when in place serving to act both as a guide in marking the stamping for trimming and also as a drilling jig.

6. A jig for the purpose specified, having in combination, a male member arranged to support a stamping, a pair of upright rods carried by the male member, a female member or marking pattern guided in vertical reciprocation on said rods, and an air cylinder and piston for raising and lowering said female member from and onto the stamping supported upon the male member.

7. A jig for the purpose specified, having in combination a male member, adapted to support a stamping, a female member, means for guiding the same in vertical reciprocation with respect to the male member, the female member having a periphery acting as a pattern to mark the stamping supported upon the male member for trimming, and provided with one or more apertures through which drills may be inserted to drill the fender, said drilled holes acting as guides for subsequent punching operations, said female member being provided with detachable sections which carry said marking devices, to change the pattern and the drill jig holes to make the jig applicable to more than one model of fender.

In testimony whereof I affix my signature.

JOSEPH O. RICHARD.
